UNITED STATES PATENT OFFICE.

ALEXANDER HEINRICH KEHRHAHN, OF FRANKFORT-ON-THE-MAIN, GERMANY, AS
SIGNOR TO THE TURNER TANNING MACHINERY COMPANY, OF PORTLAND, MAINE,
A CORPORATION OF MAINE.

MACHINE FOR TREATING HIDES, SKINS, AND LEATHER.

Application filed December 17, 1925. Serial No. 76,011.

To all whom it may concern:

Be it known that I, ALEXANDER H. KEHRHAHN, a citizen of Germany, residing in Frankfort-on-the-Main, Germany, have invented certain Improvements in Machines for Treating Hides, Skins, and Leather, of which the following description, in connection with the accompanying drawings, is a specification, like reference characters on the drawings indicating like parts in the several figures.

This invention relates to machines for treating hides, skins, leather and other like pieces of work and is illustrated as embodied in a machine designed for performing unhairing and scudding operations, although in various aspects the invention is not limited to embodiment in machines of the illustrated type or to use in performing the particular operations just referred to.

One well-known type of machine for performing operations such as those above mentioned has been provided with a bed roll of relatively small diameter employed to support the work against the thrust of a tool, the chief disadvantage of such a construction for certain classes of operation being found in the fact that the work is presented to the tool on a too narrow work supporting surface for the best results. In other prior constructions, such as that of the well-known Leidgen machine of the type shown in United States Letters Patent No. 713,118, granted Nov. 11, 1902, upon application of N. Leidgen, a broad band or bolster is utilized in presenting the work to the tool, the result being unsatisfactory in some cases since the resilient bolster is in such cases too soft in its action.

In view of the foregoing, it is an object of this invention to provide an improved machine for treating hides, skins and leather, which will not be open to the objections above stated and will be simple and durable in construction and especially efficient for the purposes intended.

To this end, and in accordance with important features of the invention, an improved work presenting means is provided comprising a bolster arranged to provide a concaved work supporting surface of considerable width and to embrace a substantial

portion of the curved surface of the work operating tool, and a yielding bed roll to support the bolster along a line extending transversely of the bolster so that a narrow strip portion of the bolster is pressed firmly but yieldingly against the operating tool whereby the advantages of both a bolster and a yielding bed roll are obtained without the disadvantages of either when used alone. By the employment of both a bolster which wraps around a substantial portion of the cylindrical surface of the tool, and a bed roll for pressing a narrow strip portion of the bolster against the tool, there is secured an arrangement by which a relatively broad strip portion on the work may be engaged by the tool with a yielding pressure sufficient to cause effective operation of the tool and by which a narrower strip portion of the work is subsequently engaged by the same tool at a higher pressure to insure the desired results upon portions of the work which may have resisted the tool while working under less pressure.

In the illustrated machine an endless bolster travels over rollers and is pressed yieldingly against a work treating cylindrical tool by means of a pneumatic bed roll which is itself freely rotatable thereby lessening friction between itself and the bolster. Means is provided for backing the pneumatic bed roll and for controlling the pressure which it exerts against the bolster, the said means comprising, in the preferred construction, a cylindrical member adapted to press upon the bed roll through contact with the bolster, the cylindrical backing member being also rotatable to lessen friction and wear between itself and the bolster.

Other features of the invention and novel combinations of parts will be described in the detailed specification and pointed out in the appended claims.

In the drawings,

Figure 1 illustrates an end view partly in section of a machine disclosing one embodiment of the invention; and

Fig. 2 is a detail view partly in section showing a modification of the invention.

In the machine illustrated in Fig. 1, there is mounted in a frame 4 a pair of arms 6 pivoted at 8 to swing between the solid line

position and that indicated by the dot and dash line 6^a. Rigidly secured to each arm 6 is a bracket 9 to the outer end of which is pivoted one end of a toggle 10, the other end of which is pivoted at 12 in the frame of the machine. For operating the toggle, means is provided of any ordinary construction (not shown) for moving the knee part 14 of the toggle. Bearings are provided in 10 the pair of arms 6 for the shaft 16 of a roller 18 which may be an idler roller or power driven as the requirements of the work and of the operations to be performed thereon may make necessary or desirable. 15 Other bearings are provided at the upper ends of the arms 6 for a shaft 20 to which is secured a roller 22 power driven by means not shown but which may comprise any of the well-known sets of gear mechanism common 20 in leather working machines. Passing around both of the rollers 18 and 22 is an endless bolster 24 which may be of rubber, or a rubber composition, with a canvas backing to secure a durable yet flexible member 25 with a smooth firm surface for supporting the work while it is being operated upon. Carried by the arms 6 are a pair of guide members 26 and 28 which, together with adjacent portions of the bolster 24 form a 30 housing for a pneumatic bed roll 30 of relatively small diameter and freely rotatable about its longitudinal axis, thereby minimizing friction between the bolster and the bed roll. Upon inspection of Fig. 1, it will 35 be observed that the bed roll 30 is located within the endless bolster 24, and between the upper and lower guide members 26, 28. Within the housing thus formed the bed roll is supported to rotate freely about a 40 longitudinal axis which is not fixed since the bed roll is "floating", that is, freely movable, within the walls of its housing. Means (not shown) is provided for controlling the degree of inflation of the pneumatic bed roll 30, such means being of any well 45 known construction. Means is provided for furnishing a backing for the pneumatic bed roll 30, the said means in the construction shown comprising a relatively large roller 50 mounted to turn idly upon a shaft 34 carried by bearings in upright levers, one of 55 which is shown at 36 pivoted at its lower end upon the bracket 9. At the upper end of each lever 36 there is connected a link 38 by means of threaded nuts 40 adjustable upon a threaded portion of the rod 38 and operative to hold the lever 36 in adjusted relation to the rod 38. At its other end the rod 38 is pivoted at 42 to a portion of the 60 arm 6. It will be understood that pressure to be applied to the bed roll 30 by means of the backing roller 32 may be adjusted as required by proper manipulation of the bolts 40 upon the two similar rods 38. Since the 65 bolster 24 should run with relative freedom

between the bed roll 30 and its backing roller 32 the latter, as well as the bed roll, is made to turn freely upon its axis. When the backing roller 32 is adjusted toward the bed roll 30 the latter is pressed to the left in 70 Fig. 1 to afford greater pressure on the work during operation of the machine.

For operating upon the work there is provided in the construction shown a bladed cylinder 50 secured to a shaft 52 rotatably 75 mounted in the frame 4 of the machine and arranged to be driven from any well-known source of power (not shown).

For feeding the work past the bladed cylinder 50, there is provided feeding means 80 comprising a pinch roll 54 mounted upon a shaft 56 journaled in the upper part of the machine frame 4 and arranged to be driven by means (not shown). When the work supporting means comprising the 85 rollers 18, 22 and the bolster 24 is in work receiving position indicated by the dot and dash line 6^a, a piece of work indicated at 90 60 is thrown over the bolster 24 so that it hangs suspended between the bladed cylinder 50 and the adjacent surface of the bolster 24. Upon starting the machine the toggles 10 are straightened to move the work supporting parts, including the bolster 24, to the left in Fig. 1 into the position indicated by the solid line showing of the bolster and its supporting rollers 18 and 22. When these work supporting parts move to the position shown, the work is 95 brought into firm contact with the pinch roller 54 which is rotating in the direction indicated by the arrow. Since the upper roller 22 is power driven to rotate in the direction the reverse of the pinch roll 54, it follows that the piece of work 60 will be 100 fed out of the machine toward the operator who stands at the right in Fig. 1, and that during this movement of the work it is 105 operated upon by the bladed cylinder 50. The bolster 24, since it laps around a 110 considerable portion of the periphery of the bladed cylinder 50, presents a relatively broad strip of the surface of the work against the bladed cylinder and this arrangement it especially effective for such 115 operations as unhairing and scudding operations upon hides and skins. While the bolster 24 causes the presentation, under a yielding pressure, of a relatively wide strip on the work to the operation of the cylinder, it is desirable to provide for a firmer 120 backing of the work along a narrower strip to insure adequate operation of the blades of the bladed tool, and this is accomplished through the operation of the relatively 125 small pneumatic bed roll 30 which backs the bolster along a relatively narrow strip where the work receives the greatest thrust of the bladed cylinder. While the pressure is greater where the bolster is backed by 130

the pneumatic bed roll 30, it is still a yielding pressure whereby work of varying thickness is accommodated while at the same time adequate pressure is provided to insure the desired operation of the blades of the working tool. In unhairing operations, for instance, most, if not all, of the loose hair will be removed by the bladed cylinder in co-operation with a portion of the bolster at the time above the bed roll 30 where the bladed cylinder operates upon a relatively broad strip of the work, whereas, where the bladed cylinder co-operates with that part of the bolster which is directly backed by the bed roll 30, the portion of the work thus operated upon at a given time is a relatively narrow strip which receives a greater pressure in the thrust of the bladed tool, thus insuring perfect work by the bladed tool without the danger of injury to the work, since this part of the work support is also yielding. In scudding operations, the loose dirt and epithelial cells are removed by the bladed cylinder operating on a relatively broad strip of the work supported by the bolster above the bed roll. Then the more resistant portions of the surface dirt and scud are removed by the bladed cylinder in co-operation with the bolster along the narrow strip where the latter is backed by the bed roll 30. By reason of the adjustment secured for the backing roller 32, the tension on both the bolster 24 and on the pneumatic bed roll 30 may be adjusted to suit requirements. It will be understood that the bolster 24 moves with the power driven roller 22 since the roller and bolster co-operate with the pinch roll 54 in feeding the work from the machine and past the bladed cylinder 50. It follows that all portions of the working surface of the bolster are presented in succession to the thrust of the cylinder while the latter is operating on the work. Hence, the bolster is worn evenly so that whatever adjustment of the pressure is effected through proper manipulation of the nuts 40 on the rod 38, all parts of the bolster are equally suited to the new working conditions effected by the adjustment. Since the wear on the bolster is equally distributed over a relatively large surface the bolster is relatively long-lived. For the same reason, adjustment for pressure with respect to the cylinder is required only at infrequent intervals.

In the modified construction shown in Fig. 2 of the drawings the bladed cylinder 50 is arranged to co-operate with a stationary bolster 62 which has its longitudinal edges securely attached to side faces of the U-shaped bed roll support 64. In this form of the invention the bolster 62 is of a size and so arranged as to provide a concave

portion which contacts with a considerable area of the periphery of the bladed cylinder 50 and is backed by a pneumatic bed roll 30 of the same construction as that disclosed in Fig. 1. For adjusting the tension of the bed roll 30 and for controlling the pressure thereof upon an intermediate portion of the bolster 62, there is provided a pressure plate 66 arranged to be moved adjustably by means of screw threaded adjusting members 68 adapted to contact with the rear face of the pressure plate 66 and to be adjusted in a well-known manner and to be secured in adjusted position by lock nuts 70, it being understood that there are a number of the adjusting members 68 for securing proper adjustment of the pressure plate 66 along its length. When the work presenting surface of the bolster 62 has become worn, the bolster may be readily removed and replaced by a fresh bolster.

Having thus described my invention, what I claim as new and desire to secure by Letters Patent of the United States is:—

1. In a machine for operating on hides, skins, leather and other like pieces of work, a tool for operating on the work, an endless bolster for supporting the work against the thrust of the tool, means co-operating with the bolster for engaging the work to feed it past the tool, and a pneumatic bed roll for yieldingly pressing the bolster against the tool.

2. In a machine for operating upon hides, skins, leather and other like pieces of work, a tool having blades for operating on the work, an endless bolster for supporting the work against the thrust of the tool, rollers over which the bolster passes, means for driving one of the rollers, a roll co-operating with the bolster for engaging the work to feed it past the tool, and a relatively small pneumatic bed roll for pressing the bolster along a relatively narrow strip against a portion of the tool.

3. In a machine for operating upon hides, skins, leather and other like pieces of work, a bladed cylinder and work presenting means relatively movable from work receiving position into co-operative relation with respect to each other, said work presenting means comprising a pair of supporting members, a bolster passing around the supporting members, and a bed roll back of a portion of the bolster, the arrangement being such that the bolster is adapted to embrace a substantial portion of the cylindrical surface of the bladed cylinder and has a narrow strip portion thereof pressed firmly against the cylinder by the bed roll.

4. In a machine for operating on hides, skins, leather and other like pieces of work, a cylindrical tool having a blade for operating on the work, work presenting means comprising a pair of supporting rollers, an

endless bolster passing around the rollers, a bed roll within the bolster, the bed roll being operative to support the bolster along a relatively narrow strip extending transversely thereof against the thrust of the tool, and the bolster being tensioned to present a broader strip portion thereof to the tool at one side of the bed roll.

5. In a machine for operating on hides, skins, leather and other like pieces of work, a tool for operating on the work, a bolster for supporting the work against the thrust of the tool, a freely movable bed roll for yieldingly pressing the bolster against the 10 tool, and a housing for the bed roll having a side open to the bolster and adapted to support the bed roll in contact with the bolster for movement therewith.

6. In a machine for operating upon hides, skins, leather and other like pieces of work, a tool having blades for operating on the work, a travelling bolster for supporting the work against the thrust of the tool, rollers over which the bolster passes, a freely rotatable bed roll for pressing the bolster 20 against a portion of the tool, and a housing for the bed roll having a side open to the bolster and adapted to support the bed roll in contact with the bolster for rotation therewith.

7. In a machine for operating upon hides, skins, leather and other like pieces of work, a bladed cylinder for operating on the work, means for rotating the cylinder, an endless 30 travelling bolster movable in a direction the reverse of the direction of movement of the cylinder, a freely rotatable pneumatic bed roll for supporting the bolster against the thrust of the bladed cylinder, and a rotary member for yieldingly backing the pneumatic bed roll.

8. In a machine for operating on hides, skins, leather and other like pieces of work, a bladed cylinder for operating on the work, 45 an endless travelling bolster for presenting the work to the bladed cylinder, a pneumatic bed roll for pressing the bolster against the periphery of the cylinder, said pneumatic bed roll being freely rotatable and located 50 within the bolster, and a rotary member contacting with one run of the bolster and operative to press against the pneumatic roll to back the latter and to control the tension thereof.

55 9. In a machine for operating upon hides, skins, leather and other like pieces of work, a bladed cylinder for operating on the work, means for rotating the cylinder, an endless bolster movable in a direction the reverse of 60 the direction of movement of the cylinder, a pneumatic bed roll for supporting the bolster against the thrust of the bladed cylinder, and a member for unyieldingly backing the pneumatic bed roll.

65 10. In a machine for operating upon hides,

skins, leather and other like pieces of work, a bladed cylinder for operating on the work, means for rotating the cylinder, an endless bolster movable in a direction the reverse of the direction of movement of the cylinder, a pneumatic bed roll for supporting the bolster against the thrust of the bladed cylinder, a member for unyieldingly backing the pneumatic member, and means for adjusting the backing member to vary the tension on the pneumatic bed roll.

75 11. In a machine for operating on hides, skins, leather and other like pieces of work, a bladed cylinder for operating on the work, an endless bolster for presenting the work to the bladed cylinder, a bed roll for pressing the bolster against the periphery of the cylinder, said bed roll being located within the bolster, and a rotary member contacting with one run of the bolster and operative to press against the bed roll to back the latter and to control the tension thereof whereby adjustment of the rotary member toward the bladed cylinder effects an increased yielding tension of the bolster.

80 12. In a machine for operating upon hides, skins, leather and other like pieces of work, a bladed cylinder stationary in space, and work presenting means movable from work receiving position into co-operative relation with respect to the cylinder, said work presenting means comprising a pair of rollers, an endless bolster passing around the rollers to be driven thereby, a bed roll within the bolster, and a roller arranged to press upon a portion of the bolster to transmit pressure to the bed roll, whereby the tension of the bolster and the pressure of the bed roll upon the bolster at the place of the thrust of the tool may be adjustably controlled.

85 13. In a machine for operating on hides, skins, leather and other like pieces of work, a tool having a blade for operating on the work, work presenting means comprising a pair of oscillatory arms, rollers mounted on the arms, an endless bolster passing around the rollers, a bed roll within the bolster, levers carried by the arms, a roller carried by the levers for pressing upon the bolster to transmit pressure therethrough to the bed roll, the bed roll being operative to support the bolster against the thrust of the tool, and means for moving the arms and the work presenting means from work receiving 90 to work presenting position and in a reverse direction.

100 14. In a machine for operating on hides, skins, leather and other like pieces of work, a tool having a blade for operating on the work, work presenting means comprising a pair of oscillatory arms, rollers mounted on the arms, an endless bolster passing around the rollers, a bed roll within the bolster, levers carried by the arms, a roller carried 105 110 116 120 125 130

by the levers for pressing upon the bolster to transmit pressure therethrough to the bed roll, the bed roll being operative to support the bolster against the thrust of the tool, and 5 means for moving the arms and the work presenting means from work receiving to work presenting position and in a reverse direction, and a pinch roll arranged to co-¹⁰ operate with the bolster to feed the work past the tool.

In testimony whereof I have signed my name to this specification.

ALEXANDER HEINRICH KEHRHAHN.
